(57) **CLAIM**

The ornamental design for an elongated implement retaining apparatus, as shown and described.

DESCRIPTION

FIG. 1 is a perspective view of an elongated implement retaining apparatus showing my new design;

FIG. 2 is a right side elevation thereof;

FIG. 3 is a top plan view thereof;

FIG. 4 is a bottom plan view thereof;

FIG. 5 is a front elevational view thereof; and,

FIG. 6 is a rear elevational view thereof.

In the drawings, the broken lines depict environmental subject matter only and form no part of the claimed design.
